UNITED STATES PATENT OFFICE.

PHILO D. BECKWITH, OF DOWAGIAC, MICHIGAN.

DESIGN FOR A STOVE-PLATE.

Specification forming part of Design No. 5,452, dated January 2, 1872.

To all whom it may concern:

Be it known that I, PHILO D. BECKWITH, of Dowagiac, in the county of Cass and State of Michigan, have invented and produced a new and original ornamental Design for a Stove-Plate, of which the following is a specification:

The nature of my design is fully represented in the accompanying photographic illustration, to which reference is made.

Figure 1 is a front view of the stove-plate, and Fig. 2 is a top view.

The plate represented is designed for the base or bottom plate of a circular stove, and the ornamentation of this plate is exposed upon the surface of the margin, as shown.

I claim as my invention—

The ornamentation for a stove-plate, as shown.

PHILO D. BECKWITH.
